CLAIM

I claim the ornamental design for a lighting apparatus, as shown and described.

DESCRIPTION

FIG. 1 is a top front perspective view of a lighting apparatus showing my design;

FIG. 2 is a top rear perspective view if FIG. 1;

FIG. 3 is an end view of FIG. 1, the opposite end view being a mirror image thereof;

FIG. 4 is a front view of FIG. 1;

FIG. 5 is a top view of FIG. 1;

FIG. 6 is a bottom view of FIG. 1; and,

FIG. 7 is a rear view of FIG. 1.
